UNITED STATES PATENT OFFICE.

JOHN V. SULLIVAN AND DAVID A. PORTER, OF SENY, GEORGIA,
ASSIGNORS OF ONE-HALF TO HENRY ARTHUR POWERS, OF
ARAGON, GEORGIA

COTTON-CHOPPER.

No. 806,988.

Specification of Letters Patent.

Patented Dec. 12, 1905.

Application filed August 24, 1905. Serial No. 275,615.

To all whom it may concern:

Be it known that we, JOHN V. SULLIVAN and DAVID A. PORTER, citizens of the United States, residing at Seney, in the county of Floyd and State of Georgia, have invented a new and useful Cotton-Chopper, of which the following is a specification.

This invention relates to cotton-choppers; and the objects of the invention are to simplify and improve the construction and operation of this class of devices and to provide a simple and improved means whereby the chopping mechanism may be thrown out of gear and the machine arranged for transportation.

With these and other ends in view, which will readily appear as the nature of the invention is better understood, the same consists in the improved construction and novel arrangement and combination of parts, which will be hereinafter fully described, and particularly pointed out in the claim.

In the accompanying drawings has been illustrated a simple and preferred form of the invention, it being, however, understood that no limitation is necessarily made to the precise structural details therein exhibited, but that changes, alterations, and modifications may be made within the scope of the invention.

In the drawings, Figure 1 is a top plan view of a cotton-chopper constructed in accordance with the principles of the invention. Fig. 2 is a longitudinal sectional view taken on the plane indicated by the line 2-2 in Fig. 1. Fig. 3 is a rear elevation, partly in section. Fig. 4 is a sectional plan detail view showing the machine out of gear. Fig. 5 is a detail side view.

Corresponding parts in the several figures are indicated throughout by similar characters of reference.

The frame of the improved machine, which is rectangular in shape, has been shown as composed of side pieces 1 and front and rear end pieces 2, 3, the side pieces being also connected by an intermediate cross-piece 4. The side pieces intermediate the cross-pieces 3, 4 are provided with bearings for a shaft or axle 5, carrying a pair of ground-engaging wheels 6 and 7, the latter of which carries a bevel-pinion 8, meshing with a bevel-pinion 9 upon a longitudinal shaft 10, which is supported

for rotation in bearings supported by the cross-pieces 3 and 4.

The shaft or axle 5 is capable of sliding laterally in its bearings, and one end of said shaft is normally extended slightly beyond the outer side of one of the frame members 1, as best seen at 11 in Fig. 1. The shaft is normally retained in this position by means of a spring 12, interposed between the wheel 7 and the adjacent frame member 1, which latter has a recess 13 for the accommodation of said spring. The principal function of the latter is to retain the bevel-pinions 8 and 9 in operative engagement with each other. It will be obvious that when the projecting end of the axle is pushed inwardly the spring will be compressed and the pinions 8 and 9 will be thrown out of engagement with each other. When the axle is thus pushed back, as will be seen in Fig. 4 of the drawings, it may be retained in this position by means of a plate 14, connected by a pivot 15 with the outer side of the frame member 1, through which the end of the axle normally projects, the plate 14 being provided at its free end with a notch 16, adapted to engage a headed stud 17, whereby it may be temporarily locked to retain the axle in the position illustrated in Fig. 4. It is obvious that the ground-engaging wheels, as well as the pinion 8, are fixedly secured upon the axle and that the latter is free to rotate in any position occupied thereby.

The shaft 10, which extends in rear of the rear cross-bar 3, carries at its rear end a hub 18, having radiating arms 19, provided at their outer ends with sockets 20 for the reception of the tangs 21 of the hoes or chopping-blades 22, which are secured therein, as by means of set-screws 23. The shaft 10 is also provided with a collar 24, secured thereon by means of a set-screw, said collar bearing against the front side of the cross-bar 4, so as to retain the pinion at the front end of the shaft in operative engagement with the pinion 8.

The frame of the machine is equipped with a draft-yoke 25 and with handles 26, connected by rungs 27 and supported by braces 28.

It will be seen from the foregoing description that this improved cotton-chopper is of extremely simple construction and that it may be readily manipulated to chop out the super-

fluous plants from a row of cotton. The ground-engaging wheels will straddle the row, and the operator may at will raise and lower the rear end of the machine and manipulate the latter to chop out the plants at the desired points. When the machine is to be transported and it is desired to throw the chopping mechanism out of operation, the axle 5 may be pushed laterally against the

5 tension of the spring 12 and secured by the plate or latch member 14 in the position shown in Fig. 4, when it is obvious that said axle may rotate without imparting motion to the chopper-carrying shaft.

15 Having thus described the invention, what is claimed is--

In a cotton-chopper, a frame one side member of which is provided with a recess in the inner side thereof, a laterally-slidable axle extending through and concentric with said recess, and transporting-wheels upon the axle; a spring coiled upon the latter, seated in the recess of the frame and bearing against the proximate transporting-wheel, said axle projecting normally through the distant side

piece of the frame; a latch member pivotally connected with the latter side piece and normally resting upon the protruding end of the axle, and a stud adapted for engagement with said latch member when the projecting portion of the axle is withdrawn against the tension of the spring upon the latter; in combination with a bevel-pinion upon the axle, and a chopper-carrying shaft supported for rotation longitudinally in the frame and having at the front end thereof a bevel-pinion intermeshing with the bevel-pinion upon the axle; the spring coiled on the axle and seated in the recess of the frame serving to hold the bevel-pinnions normally in mesh with each other when the latch member is raised out of the path of the protruding end of the axle.

In testimony that we claim the foregoing as our own we have hereto affixed our signatures in the presence of two witnesses.

JOHN V. SULLIVAN.
DAVID A. PORTER.
